UNITED STATES PATENT OFFICE.

ERNST MÜLLER, OF BERLIN, AND ALFRED KÄYSER, OF WILMERSDORF, NEAR BERLIN, GERMANY, ASSIGNORS TO DÜBELWERKE GESELLSCHAFT MIT BESCHRÄNKTER HAFTUNG, OF BERLIN, GERMANY, A CORPORATION OF GERMANY.

ELASTIC BEDDING-PLATE.

1,105,368.

Specification of Letters Patent. Patented July 28, 1914.

Application filed October 10, 1913. Serial No. 794,450.

To all whom it may concern:

Be it known that we, ERNST MÜLLER, railway officer, residing at Wartenburgstrasse 9, Berlin, Germany, and ALFRED KÄYSER, engineer, residing at Eisenzahnstrasse 8, Wilmersdorf, near Berlin, Germany, both subjects of the German Emperor, have invented new and useful Improvements in Elastic Bedding-Plates, of which the following is 10 a specification.

The present invention relates to a novel, elastic bedding plate for the construction of the permanent way on railway lines. Such plates are used chiefly when the rails 15 are laid on a solid bed, as is the case with mining railways, turntables, centesimal weighbridges and the like. The plates are made either of wood or of leather, felt or other materials used in building. Plates 20 made of wood are entirely unserviceable. Therefore special machines have been designed, which treat the wood under very high pressures. But also wooden plates 25 which had been treated in such a manner did not meet their purpose under heavy strains, so that the more expensive plates of felt and chromium leather or the like had to be used.

According to the present invention the 30 bedding plates are again made of wood. It has been found that the destruction of the wooden bedding plates hitherto employed was the result of the fact that the wood fibers which are parallel to each other were not 35 sufficiently closely and tightly united to each other so as to be able to resist the strains, in particular the pressure and the shocks. The wooden plates therefore gradually became wider and thinner, whereby the cohesion 40 of the fibers was disrupted and the whole bedding plates were destroyed. This tendency of the wooden plates to spread and disintegrate under pressure transversely to the fibers can, according to the present invention, be successfully met by reinforcing the wooden plates with iron, steel and the like metal. Such reinforcing may be obtained by means of straps, caps, wiring, webs 45 or the like. The reinforcements must be 50 only so arranged, that they prevent the expansion of the wood transversely to the direction of the fibers.

In the accompanying drawing several constructional forms of the new plate are shown in plan and section. 55

Figures 1, 2 and 3 represent bedding plates provided with several modifications of the reinforcing means. Fig. 2^a is an end view in section of Fig. 2, and Fig. 4 is a 60 similar view of Fig. 3.

Fig. 1 shows a plate *a*, the short ends of which are wrapped with wire *b* or metal straps *b*¹. In the latter case the straps are preferably secured to the plate *a* by means of lugs cut into the straps and bent by means 65 of a sharp tool, which lugs *b*² enter into the wood. In the former case it is sufficient to drive the ends of the wire into the wood or twist them together.

Fig. 2 shows a plate *a*, in which as evident 70 from the section Fig. 2^a a web *c* has been driven, which has preferably an undulating shape. The web *c* is split at both ends and the split ends are bent over the outside of 75 the wood.

With the constructional form according to Fig. 3 the plate is fitted with caps at both ends. These caps *d* may be stamped of any suitable sheet metal. They are secured to 80 the wood by means of small indents *d*².

Fig. 4 shows a special constructional form of the caps. In this case the cap is made of band metal, and has a web *d*¹ which is driven into the cross grain of the plate. The reinforcements may also be combined with 85 each other in various ways. For instance, the bands and wires according to Fig. 1 may be employed in combination with the webs according to Figs. 2 and 2^a and the latter in combination with the caps *d* (Fig. 3). 90 The straps or wires *b*, *b*¹ may also be provided at one or at several parts of the middle of the plates.

We claim:

1. In combination with an elastic bedding 95 plate, of suitable material, reinforcing means comprising metallic caps inclosing the ends of said plate, adapted to prevent spreading thereof.

2. In combination with an elastic bedding 100 plate of suitable material, reinforcing means comprising metallic caps inclosing the ends of said plate, adapted to prevent spreading thereof, lugs formed integrally with each of

- said caps for engagement with said plate, the ends of said caps being recessed internally to form V-shaped members for engaging said plate.
- 5 3. In combination with an elastic bedding plate, reinforcing strips driven edgewise into the ends of said bedding plate, each of said strips having bifurcated projecting ends bent in opposite directions to embrace the 10 sides of said bedding plate.
4. In combination with an elastic bedding plate, corrugated metallic reinforcing strips driven edgewise into the ends of said bedding plate, each of said strips being provided with bifurcated projecting ends but at 15 right angles in opposite directions to embrace the sides of said bedding plate.
5. In combination with an elastic bedding plate, reinforcing strips driven into the ends 20 thereof, each provided with bifurcated projecting ends bent in opposite directions to embrace the side of said bedding plate and

clenched over the base and top thereof respectively.

6. In combination with an elastic bedding 25 plate, means for reinforcing the same comprising each a flat strip of metal corrugated transversely and driven edgewise into the ends of said bedding plate, bifurcated partitions on said strips projecting beyond the 30 sides of said bedding plate and bent up in opposite directions to embrace said sides and having the terminals thereof turned over against the base and top of the bedding plate respectively. 35

In testimony, that we claim the foregoing as our invention, we have signed our names in presence of two witnesses, this 25th day of September 1913.

ERNST MÜLLER.
ALFRED KÄYSER.
